CHILD'S DRINKING GLASS

Edith Rosalie Thompson and Clifford O.
Thompson, Hawthorne, Calif.

Application February 14, 1952, Serial No. 18,521

Term of patent 14 years

(Cl. D36—8)

To all whom it may concern:

Be it known that we, Edith Rosalie Thompson and Clifford O. Thompson, citizens of the United States of America, residing at Hawthorne, county of Los Angeles, and State of California, have invented a new, original, and ornamental Design for Child's Drinking Glass, of which the following is a specification, reference being had to the accompanying drawing, forming a part thereof, wherein:

We claim:

The ornamental design for a child's drinking glass, as shown.

EDITH ROSALIE THOMPSON.
CLIFFORD O. THOMPSON.
